UNITED STATES PATENT OFFICE

2,100,547

SUPPLEMENTARY CONTROLLED DRAFT FOR FUEL BURNERS

Clarence Verne Martin, Toledo, Ohio, assignor to
The National Supply Company, Pittsburgh,
Pa., a corporation of Pennsylvania

Application November 3, 1934, Serial No. 751,371

2 Claims. (Cl. 236—26)

This invention relates generally to the control of supplementary air for fluid fuel burners for steam boilers and more specifically to the control of steam jet supplementary air boosters.

This invention may be advantageously applied to steam generating devices wherein the control of the supplementary air to the burning fuel is governed by generated steam of the boiler under constant pressure irrespective of the steam load being furnished. Such a device is disclosed in Letters Patent No. 1,758,828, issued May 13, 1930. It is a well known fact that fuel losses in any fuel burning system are caused by either "over-ventilation" or "underventilation". When an excessive demand is made upon the steam generating system, more fuel and more air are naturally required to produce more steam. While it is possible to maintain a proper relation between the fuel and the air under normal conditions, it is sometimes difficult to do so when excessive demands for steam are imposed upon the system. When insufficient air is supplied to properly support combustion a portion of the unburned products pass out of the stack in the form of carbon monoxide along with the flue gases. An increased supply of oxygen in the combustion chamber will convert carbon monoxide into carbon dioxide forming a complete product of combustion. Boilers designed to operate under automatic control depend upon the natural draft of the boiler stack to draw the air into the combustion chamber to mix with the fluid fuel being burned. The draft provided by the stack is not sufficient to properly support the combustion of the increased volume of fuel demanded by reason of a sudden increase in the load of steam reducing the boiler pressure.

Such an increase in the steam load which causes the reduction of the boiler pressure will operate the fuel and air valves and increase the combustion but it is limited by reason of the natural stack draft of the boiler. In locomotive art this is corrected by providing an exhaust steam jet in the stack to increase the flue draft but in the instance of the application this is impractical because of the remoteness of the steam load.

Again if a constant jet of steam were to be exhausted in the boiler stack the efficiency of the boiler would be materially reduced because the induced draft would be too great and a large amount of the heat would be lost up the stack since a greater portion of the operation of the boiler is under a light load.

The principal object of this invention is to provide means for automatically controlling steam in

a boiler stack to produce the proper supplementary air draft in the combustion chamber to effect complete combustion of the fuel when it is increased by reason of a demand for more steam within the boiler.

This may be accomplished by providing means, arranged to be actuated by variations of steam pressure, for controlling the volume of steam exhausted in the stack, thereby producing a stack draft, effecting the supply of supplementary air to the combustion chamber which is proportional to the variation of the amount of fuel supplied to said combustion chamber.

Another object is to provide means for controlling the stack draft of a boiler concurrently with the control of supplementary air intake.

Another object is to provide means for controlling a steam jet in the stack of a boiler by the operation of a draft valve which is automatically regulated by the steam pressure within the boiler.

Other advantages and objects will appear in the following description.

In the accompanying drawings wherein I have illustrated a practical embodiment of the principles of my invention, Fig. 1 is a side elevation of a boiler illustrating the application of my device thereto.

Fig. 2 is a top plan view of the damper valve construction showing my steam jet control valve applied thereto.

Fig. 3 is a side elevation of the damper box and the controls therefor illustrating the application of my control valve thereon.

Fig. 4 is an enlarged sectional view taken longitudinally of my control valve illustrating the operative connection thereof with the damper valve parts being broken away.

Fig. 5 is a sectional view taken on the line 5—5 of Fig. 4.

Referring to Figs. 1 to 3 of the drawings, 10 represents a boiler having a stack 11 and a steam dome 12. 13 represents a fuel burner unit which is provided with burners positioned within the combustion chamber of the boiler and fed by the fuel line 14. The flow of the fuel is determined by the vacuum controlled regulator 15 which is placed in the fuel supply line between the burner valve 16 and the gate valve 17. 18 is a fuel strainer housing which is placed in the fuel line between the gate valve 17 and the fuel supply line 14. 20 represents the pilot burner control line which is tapped into the fuel supply line ahead of the regulator.

21 represents the opening of the vertical air

supply conduit 22 which is connected to one end of the horizontal conduit 23, the other end of which opens into the combustion chamber under the burners.

5   24 represents a rectangular butterfly damper valve arranged to control the opening of the conduit 22 and consequently the air passing therethrough. This valve is supported at each
10   end by the members 25 and 26 having the knife edges 27 resting in the bearing grooves 28 supported on the sides of the vertical conduit 22.

29 represents a damper motor which is provided with a flexible diaphragm connected to the damper valve 24 by means of the arm 30 for operating the same. The damper motor is provided with a pressure chamber above the diaphragm which is connected by the pipe line 31 to the fuel burner pressure chamber below the diaphragm of the fuel regulator 15. The chamber above the diaphragm of the regulator is a vacuum chamber which is provided with the exhaust pipe line 32 connected to the boiler governor 33 mounted on top of the steam dome 12. The structure and operation of the steam governor and the regulator is described in the above mentioned Letters Patent.

Thus the steam governor 33, which is controlled by the steam pressure of the boiler, operates the regulator 15 which in turn controls the amount of fuel to the burners and the pressure of this fuel, which is a direct function of the volume of the fuel delivered to the burners, operates the damper motor 29 which controls the degree of the opening of the butterfly valve 24 in proportion to the amount of fuel delivered to the burners.

This apparatus operates on small differences in pressure but the apparatus controlling the air to the combustion chamber does not furnish an adequate amount of air to supply the need of the burning fuel because the draft through the combustion chamber to the stack is not adequate to carry the volume of air required for burning the increased amount of fuel. This results in underventilation until the draft builds up and during this period the unburned fuel passes out the stack which lowers the efficiency of the boiler.

50 Again, excessive demands for increased steam pressure which increase the amount of fuel required often exceed the capacity of the stack to develop a sufficient draft to supply the proper amount of oxygen for combustion. This sometimes is due to the physical location of the boiler and sometimes the weather conditions.

To avoid these difficulties and to provide sufficient oxygen to the combustion chamber I provide the steam jet 34 within the stack 11 to create an increased draft which increases the volume of air drawn through the combustion chamber.

The jet 34 is supplied with steam through the pipe 35 which is connected to the steam control valve 36. The other side of the valve is connected to the steam dome 12 through the pipe 37. The steam valve comprises the casing 38 which in this instance is an integral part of the bearing member 28 supported by the fuel burner unit frame member on the side of the vertical conduit 22. The casing is bored out as at 39 to receive the cylindrically shaped rocker valve plug 40. The axis of the valve 40 is the same as that of the knife edge 27 of the member 25.

The inner end of the valve 40 is provided with a vertically disposed transverse lug 41 arranged to be operatively received within the bifurcated end 42 of the member 25.

Adjacent the outer end of the valve 40 the casing 38 has secured thereto a cap or closure member 43 by means of the bolts 44. The center of the cap is provided with a hole 45 arranged to permit the escape of any fluids trapped within the casing. 10

Adjacent each end of the cylindrical portion of the valve 40 is provided with annular lubricating grooves 46 and 47 to seal and lubricate the valve within the casing. The groove 46 is fed from the grease cup 48 through the stopcock 49 and the 15 passageway 50. The grooves 47 receive their lubrication through the longitudinal slot 51 in the casing 38 which connects the passage 50 to said grooves.

Intermediate of the grooves the valve 40 is 20 provided with the port 52 disposed horizontally and transversely through the diameter thereof when the valve is in its open position, as shown in Figs. 4 and 5. In this position the ends of the port 52 are arranged to register with their corresponding openings in the casing 38 which connect the steam lines 35 and 37. 25

Thus when the butterfly damper valve 24 has been rotated from its position as shown in dotted lines in Fig. 3 to the vertical position shown in Fig. 4 the member 25 causes the valve 40 to rotate so that the port 52 is fully open and permits steam to pass therethrough.

When the steam pressure of the boiler has been diminished sufficiently to decrease the vacuum created by the governor 33 the regulator 15 will operate to admit more fuel to the burners. This creates a greater pressure in the fuel side of the regulator which becomes effective in the damper motor 29 through the pipe 31 to open the damper as the volume of the fuel being fed to the burners is increased. The movement of the damper valve 24 operates the steam valve 40 to permit steam to exhaust through the jet 34 in the stack, thereby creating sufficient air draft through the combustion chamber to obtain complete combustion of the increased volume of fuel.

The degree of operation of the air valve 24 is determined by the steam pressure and this valve in turn controls the degree of stack booster draft by operating the valve 40. By properly setting these valves I am enabled to automatically obtain the proper adjustment for complete fuel combustion at all times.

While in the embodiment of my invention illustrated in the drawings, I have shown the steam jet nozzle located at the base of the stack, it will be understood that the location of the same may be varied without departing from the scope of my invention, the object in view being to produce by means of the steam jet the desired draft in the combustion chamber. 55 60

The term "supplementary air" as used herein designates the additional air supplied to the combustion system in excess of that possible to be supplied by natural draft sources. 65

I claim:—

1. In apparatus for controlling a draft inducing stack jet in a fluid fuel fed boiler, the combination of a boiler governor actuated in response to the steam demand on said boiler, a regulator operated by said governor for controlling the pressure of the fuel fed to said boiler, and valvular means operated by the pressure of the fuel for 70 75

controlling the amount of steam fed to the stack jet.

2. In apparatus for controlling a draft inducing stack jet in a fluid fuel fed boiler, the combination of a boiler governor actuated in response to the steam demand on said boiler, a regulator operated by said governor for controlling

the pressure of the fuel fed to said boiler, a damper for controlling the air fed to said boiler, a motor operated by said fuel pressure for actuating said damper, and valvular means actuated by the movement of the damper for controlling 5 the amount of steam fed to the stack jet.

CLARENCE VERNE MARTIN.
